UNITED STATES PATENT OFFICE.

FREDERICK C. BAKER, OF PORTLAND, OREGON, ASSIGNOR TO THE PHOENIX GLASS COMPANY, OF PITTSBURGH, PENNSYLVANIA, A CORPORATION OF WEST VIRGINIA.

DESIGN FOR A BOWL FOR INDIRECT LIGHTING.

49,249.

Specification for Design.

Patented June 27, 1916.

Application filed May 18, 1916. Serial No. 98,463. Term of patent 7 years.

To all whom it may concern:

Be it known that I, FREDERICK C. BAKER, a citizen of the United States, residing at Portland, in the county of Multnomah and State of Oregon, have invented a new, original, and ornamental Design for a Bowl for Indirect Lighting, of which the following is a specification, reference being had to the accompanying drawing, forming part thereof.

Figure 1 is a bottom view of a bowl for indirect lighting, showing my new design. Fig. 2 is a side view of the same.

I claim:

The ornamental design for a bowl for indirect lighting, as shown.

FREDERICK C. BAKER.
